US00D928117S

(12) **United States Design Patent** (10) **Patent No.:** **US D928,117 S**
Levine et al. (45) **Date of Patent:** **** Aug. 17, 2021**

(54) **HEADSET**(71) Applicant: **New Audio LLC**, New York, NY (US)(72) Inventors: **Jonathan E. Levine**, New York, NY (US); **Drew Stone Briggs**, Seattle, WA (US); **Marten Andersson**, Malmö (SE); **Thomas C. Wilson**, Brooklyn, NY (US)(73) Assignee: **New Audio, LLC**, New York, NY (US)(**) Term: **15 Years**(21) Appl. No.: **29/743,351**(22) Filed: **Jul. 21, 2020****Related U.S. Application Data**

(62) Division of application No. 29/668,788, filed on Nov. 1, 2018, now Pat. No. Des. 893,453, which is a division of application No. 29/596,857, filed on Mar. 10, 2017, now Pat. No. Des. 832,811, which is a division of application No. 29/535,635, filed on Aug. 7, 2015, now Pat. No. Des. 781,265.

Primary Examiner — Paula Allen Greene(74) *Attorney, Agent, or Firm* — Holzer Patel Drennan(57) **CLAIM**

The ornamental design for a headset, as shown and described.

DESCRIPTION

FIG. 1 is a perspective view of a headset showing our new design;

FIG. 2 is a front elevational view thereof.

FIG. 3 is a back elevational view thereof.

FIG. 4 is a first side elevational view thereof.

FIG. 5 is a second side profile view thereof.

FIG. 6 is a top plan view thereof; and,

FIG. 7 is a bottom plan view thereof.

1 Claim, 5 Drawing Sheets(56)
